[57] CLAIM

The ornamental design for food tray, as shown and described.

DESCRIPTION

FIG. 1 is a top perspective view of a food tray showing my new design, and

FIG. 2 is a top plan view thereof;

The end of the tray opposite that shown in FIG. 1 is an exact mirror image of the end shown. The bottom of the tray is a smooth planar surface curved at the front and rear edges to match the curvature of the ends.
